DESIGN FOR A DISPLAY CASE FOR WRIST WATCHES AND THE LIKE

William Helbein, New York, N. Y.

Application October 6, 1944, Serial No. 115,651

Term of patent 14 years

(Cl. D80—5)

To all whom it may concern:

Be it known that I, William Helbein, a citizen of the United States, residing at New York, in the county of New York and State of New York, have invented a new, original, and ornamental Design for a Display Case for Wrist Watches and the like, of which the following is a specification, reference being had to the accompanying drawing, forming a part thereof.

In the drawing:

Fig. 1 is a perspective view of a display case for wrist watches and the like, in closed position, showing my new design;

Fig. 2 is a similar view in the open position;

Fig. 3 is a front elevational view of Fig. 2; and

Fig. 4 is an enlarged side elevational view of the same.

I claim:

The design for a display case for wrist watches and the like, as shown.

WILLIAM HELBEIN.
